Daniel C. Pierron(57) **CLAIM**

The ornamental design for an inflatable booster seat, as shown and described.

DESCRIPTION

FIG. 1 is a front perspective view of an inflatable booster seat according to the present invention.

FIG. 2 is a front elevation thereof.

FIG. 3 is a rear elevation view thereof.

FIG. 4 is a left elevation view thereof.

FIG. 5 is a right elevation view thereof.

FIG. 6 is a top plan view thereof; and,

FIG. 7 is a bottom plan view thereof.

The broken lines depict environment elements of the inflatable booster seat that form no part of the claimed design.

1 Claim, 6 Drawing Sheets(56)
